07-145. OR D 12,757 EX

No. 12,757

Feb 7, 1882

UNITED STATES PATENT OFFICE.

GEORGE WILKINSON, OF PROVIDENCE, RHODE ISLAND, ASSIGNOR TO
GORHAM MANUFACTURING COMPANY, OF SAME PLACE.

DESIGN FOR A HANDLE FOR ARTICLES OF TABLE-WARE.

SPECIFICATION forming part of Design No. 12,757, dated February 7, 1882.
Application filed November 2, 1881. Term of patent 7 years.

To all whom it may concern:

Be it known that I, GEORGE WILKINSON, a citizen of the United States, residing at Providence, in the county of Providence and State of Rhode Island, have invented and produced a new and original Design for the Handles of Articles of Table-Ware, of which the following is a specification, reference being had to the accompanying photograph, forming part thereof.

Figure 1 is a view of the fork. Fig. 2 is a view of the knife. Fig. 3 is a view of the spoon, these three views being deemed necessary to fully illustrate my design.

That portion of my design designated A in Figs. 1, 2, and 3 assumes the form of an elongated panel adapted to inclose any suitable ornamental figure. At the points designated

B are transverse rectangular panels inclosing two rosettes, C. These features designated A, B, and C constitute the leading features of my design, although I have shown two of the panels A ornamented with the figure of a boy and one with the figure of a girl. Any other suitable ornament may be employed in their stead.

I claim as my invention—

The design for the handles of articles of table-ware, consisting of the elongated panel A, adapted to inclose any suitable ornamental figure, and the transverse panel B, inclosing the two rosettes C, substantially as herein shown.

GEORGE WILKINSON.
